UNITED STATES PATENT OFFICE

EDWALL JAMES BAUMÉ, OF LONG BEACH, CALIFORNIA

LOCK

Application filed July 6, 1932. Serial No. 621,009.

My invention relates generally to locks and latches for doors and like closures, and particularly to that type in which only two axially perpendicular holes need be bored in a door to prepare it for installation, and it has for its prime object the provision of a lock of the above character in which the spindle is held against rotative motion by the latch bolt carrier, the knobs being rotatable around said spindle, with means for locking the outer door knob to the spindle to prevent relative rotation and thus preventing operation of the retractor from the outside, adjustable set back means for the latch bolt and a bumper for limiting the retractive movement of the latch bolt carrier to a predetermined amount.

Another object is to provide a lock of the above character which will be cheap and simple in construction and of a maximum of simplicity and efficiency in operation.

Other objects and advantages will appear hereinafter and, while I have shown and will describe the preferred form of my invention I wish it to be specifically understood that I do not limit myself to such preferred form, but that various changes and adaptations may be made therein without departing from the spirit of my invention.

In the drawings accompanying and forming a part hereof:

Fig. 1 is a top plan of my lock as it appears in its position of use.

Fig. 2 is a longitudinal section through Fig. 1, with the spindle in elevation.

Fig. 3 is a central longitudinal section through the spindle, partly in elevation, showing the same in its normal position.

Fig. 4 is a view similar to Fig. 3, but showing the same in its locked position, locking one of the knobs against relative rotation to the spindle.

Fig. 5 is a fragmentary perspective view of the inner end of the inner or free knob.

Fig. 6 is a similar view of the inner end of the outer or lockable knob.

Fig. 7 is a fragmentary sectional view showing the lock in its locked position.

Fig. 8 is a top plan of the complement parts

of the latch bar and carrier in their disassembled positions.

Fig. 9 is a side elevation of the parts shown in Fig. 8.

Fig. 10 is a side elevation of the latch bolt carrier and latch bolt assembled ready for use.

Fig. 11 is a bottom plan of Fig. 10.

Fig. 12 is a side elevation of the locking member or key.

Fig. 13 is a side elevation of the portion of the spindle in which the locking member or key is slidably mounted.

Fig. 14 is a left hand elevation of Fig. 13.

Fig. 15 is a sectional detail of a portion of the spindle.

Fig. 16 is a central transverse section through my lock in its position of use in a door.

Referring to the drawings my device comprises the stationary spindle generally designated as "A", and comprising a central portion 18, rectangular in transverse section and having extending in longitudinal alignment from one end an elongated hub 19, and from its other end a shorter hub 20.

Formed in the outer end of the long hub 19 is a recess or socket 21, and provided through the spindle from the bottom of this recess to the other end of the spindle is and centrally thereof is an aperture 22. Provided in one of the narrow edges of the rectangular portion 18 is a narrow slot 23 which opens into the aperture 22, and this slot extends from near one end of the portion 18 to the end of the short hub 20.

Slidably mounted within the aperture 22, to slide longitudinally, is the shank 24 of the locking member or key from the side of which and near one end projects the locking plate 25 which extends through the slot 23. Rotatably mounted upon the shorter hub 20 of the spindle, held positioned by means of the circumferential groove 26 and pin 27 is the auxiliary or emergency retractor 28, the inner end of which has provided therein a concentric recess 29 into which the adjacent end of the portion 18 projects, a projecting lip 30 being provided which is adapted to engage the abutments 42 and 43 of the latch bolt car-

rier and retract the same when said auxiliary member is rotated. My latch bolt carrier, generally designated as "C" comprises a substantially rectangular member 32, through 5 which is provided a rectangular slot 33 arranged for the reception of the rectangular portion 18 of the spindle whereby said spindle is held against relative rotation. The spindle extends through slot 33 at right 10 angles to said latch bolt carrier and said slot 33 is of a length sufficient to permit said latch bolt carrier to be moved inwardly the distance required to draw back the latch bolt 15 from engagement with the striker or keeper plate to release the door or other closure.

As best shown in Fig. 4, the latch bolt carrier is provided at one end with an enlarged portion 34 and provided centrally through this enlarged portion to extend lengthwise of 20 the carrier is a screw threaded opening 35 in which is operatively mounted the screw threaded end of the latch bolt 36. The innermost end of this enlarged portion also acts as a bumper for limiting the retractive movement of the latch bolt carrier as hereafter explained. Surrounding the sides of this enlargement 34 is a spring support 37, the inner end of which is arranged to pass through the slot 33 and is provided at each side of said slot 30 with arcuate wings 38 for contact with the outer periphery of the knob shanks, the other end being slotted for the passage of the end of the latch bolt 36. A rectangular washer 39 is provided to extend across this slotted end and serves as a bearing for the inner end of 35 the latch bolt spring 40. The other end of the spring 40 bears against the inner end of the nose 41 of the latch bolt and acts to yieldably hold said latch bolt in its outermost position. Provided at the other end of the latch bolt carrier 32 at the edges of the slot 33 are pairs of abutments 42 and 43 and joining these abutments, at right angles thereto, and at the extreme end of the slot 33 is a cross 40 member 44 which coacts with the lip 25 of the locking member to hold the same in its operative position when locking the outer knob and spindle together. Screw threadedly mounted at one end upon the threaded end 45 of the shank 24, and projecting a short distance into the recess 21 is a push bar 45 which extends to and through an elongated recess 47, in the inner knob and terminates at the outer side thereof in a knob or button 48 by means of which said shank may be manually 50 forced inwardly. Provided within the recess 21, between the inner end thereof and the adjacent end of the push bar 45, is a coil 55 spring 49 which acts to normally hold said push bar and the shank 24 with its lip 25 in its outermost neutral position.

The inner knob comprises a shank or sleeve 50 and the knob 51, provided centrally therethrough with an opening 52 for the reception 60 of the spindle and provided in its inner end

with an enlarged concentric recess 53, for the reception of one end of the enlarged portion 18, and a peripheral projection or lip 54 for engagement with the abutments 42 which serves as a retractor for the latch bolt carrier. 70 Provided within the shank 50 near the inner end thereof is a concentric recess or groove 55, the inner end of which is adapted for engagement with the end of a dog 56. The other end of the dog 56 is pivotally mounted within a kerf 57 formed in the outer periphery of the elongated hub 19, and is held normally pressed outwardly by a flat spring 58 or by any other suitable means. This construction serves to hold said knob and shank securely 80 but rotatably positioned upon the spindle. An opening 59 is provided through the shank 50 immediately opposite the free end of the dog 56 so that by the insertion of a suitable instrument such as a small nail or the like 85 said dog may be forced inwardly into the kerf 57 and out of the recess 55 and permit the removal of the shank 50 and its knob 51. The outer knob comprises the shank or sleeve 60 and the knob 61, provided centrally therethrough with a central opening 62 for the reception of the shank 63 of the auxiliary retracting member 28, a slot 64 being provided in the extreme outer end thereof for the reception of a suitable rotating member such 90 as the edge of a coin or the end of a screw driver. The inner end of the shank 60 terminates in a peripheral projection or lip 68 for engagement with the abutments 43 of the latch bolt carrier. 100

Provided within the inner end of the shank 60 is a concentric recess 66 within which is positioned the auxiliary retractor member 28, and in the wall of this recess is provided a slit 67 which normally registers with the slot 23 105 of the spindle so that when the locking plate 25 is moved to its locking position (as best shown in Fig. 4) it will extend partly into said slot and partly into slit 67 thereby locking the spindle and shank together 110 against relative rotation. Shank 60 is provided at its inner end with a projecting lip 68 which coincides with the projecting lip 30 of the member 28 and acts as a retractor for the latch bolt carrier when the outer knob is 115 rotated. A circumferential groove 69 is provided around the outer periphery of the auxiliary retractor member 28 and an opening 70 is drilled through the shank 60 in such manner that a pin 71 when positioned within said opening 70 will project partly into said groove and lock said retractor and shank together against relative longitudinal movement while at the same time permitting relative rotation. 120

Having described my invention what I 125 claim is:

1. In a lock of the character described a bolt adapted to be reciprocated to and from extended position, a latch bolt carrier to which said bolt is adjustably connect- 130

ed, said carrier being substantially rectangular in side elevation and having a rectangular slot therethrough, a non-rotatable spindle arranged axially perpendicular to said carrier and being provided centrally of its length with a rectangular portion adapted to fit within said carrier slot, a substantially key shaped locking member slidably mounted within said spindle slidably lengthwise, the rectangular portion of the spindle being slotted to permit the passage therethrough of the locking plate of said locking member, a pair of tubular sleeves surrounding said spindle, one for each end thereof, and independently rotatable therearound, the inner ends of said sleeves terminating in segmental portions adapted to cooperate with said latch bolt carrier to retract the same upon the rotation of said sleeves, a slit in the inner end of one of said sleeves adapted to register with the slot of the spindle and receive a portion of the locking plate to lock said spindle and sleeve against rotative movement relatively, means to rotate said sleeves, a spring support supported by said carrier and bolt, slidably longitudinally thereof and having its inner end bearing against said sleeves and its outer end extending across the outer end of said carrier, and a coil spring surrounding said latch bolt between the outer end of said spring support and the nose of said bolt.

2. In a lock of the character described a bolt adapted to be reciprocated to and from extended position, a bolt carrier for said bolt, said carrier being substantially rectangular in side elevation and having a rectangular slot therethrough, a spindle arranged axially perpendicular to said carrier and being provided with a rectangular portion adapted to fit slidably but non-rotatably within said slot, a substantially key shaped locking member slidably mounted in said spindle to slide lengthwise thereof, the rectangular portion of said spindle being slotted to permit the projection of the locking plate of said key, a pair of tubular sleeves surrounding spindle one for each end thereof and extending from the outer ends of said spindle to the sides of said bolt carrier and being independently rotatable around said spindle, the inner ends thereof terminating in segmental portions adapted to cooperate with said latch bolt carrier and retract the same upon the rotation of either of said sleeves, a slit in the inner end of one of said sleeves adapted to register with the slot in the spindle for the reception of a portion of said locking plate and lock said sleeve and spindle against relative rotation, means to rotate said sleeves, a spring support supported by said bolt carrier and slidably longitudinally thereof having its inner end bearing against the inner ends of said sleeves and its outer end extending across the outer end of said carrier, a rectangular washer bearing against the outer

end of said spring support, and a coil spring surrounding said latch bolt between the nose thereof and said washer arranged to maintain said carrier and bolt in their extended position.

3. A lock of the character described comprising a spindle having its medial portion rectangular in transverse cross section and a central bore therethrough, a locking device including a shank and a locking plate slidably mounted in said bore, said rectangular portion being slotted for a portion of its length for the passage of said locking plate, a latch bolt carrier arranged axially perpendicular to said spindle and having a slot therethrough in which the rectangular portion of the spindle is mounted, said slot and rectangular portion coacting to prevent rotation of said spindle, a latch bolt screw-threadedly mounted at one end in one end of said carrier capable of longitudinal adjustment relative thereto, a cross bar in the opposite end of said carrier adapted for co-operation with said locking plate to lock the same in its effective locking position, a pair of shanks surrounding said spindle, one for each end thereof and extending from the outer ends of the spindle to opposite sides of said bolt carrier capable of rotation around said spindle and terminating at their inner ends in segmental projections adapted for engagement with said carrier whereby partial rotation of said shanks will retract said carrier and bolt, a slit in the inner end of one of said shanks adapted to register with the slit in the rectangular portion and receive a portion of said locking plate whereby relative rotation between said shank and spindle is prevented, means to rotate said sleeves, a spring support supported by said bolt carrier and slidably lengthwise thereof having its inner end resting against the inner ends of said shanks and its outer end extending across the outer end of said carrier and resilient means between said spring support and the outer end of said latch bolt adapted to normally maintain said bolt and carrier in their extended positions.

4. In a lock of the character described a bolt adapted to be reciprocated longitudinally to and from extended position, a bolt carrier adapted to reciprocate said bolt, yieldable means normally to hold said carrier and bolt in their extended position, a non-rotatable spindle arranged axially perpendicular to the bolt carrier and passing through the same whereby the spindle is held against rotation relative to said carrier, a knob for each end of said spindle rotatable therearound, each having an extended shank surrounding said spindle terminating at its inner end at the side of said carrier and having segmental projections adapted for co-operation with said carrier whereby rotation of said knobs and shanks will retract

said carrier and bolt from their extended position, said knobs being independently rotatable, and means between said spindle and one of said shanks for locking the same 5 against relative rotation.

5. In a lock of the character described a bolt arranged to be reciprocated to and from extended position, a bolt carrier for said bolt in which the same is adjustably mounted, 10 a spindle the axis of which is arranged axially perpendicular to the axis of said carrier and bolt, said carrier cooperating with said spindle to prevent rotation thereof.

6. In a lock of the character described a 15 bolt adapted for lengthwise reciprocation to and from extended position, means to yieldably hold said bolt in its extended position, a bolt carrier in which said bolt is mounted, a non-rotatable spindle arranged axially perpendicular to said carrier and passing through the same, the engagement between said carrier and spindle being arranged to prevent rotation of said spindle relative to the carrier, tubular shanks surrounding said 25 spindle, one for each end thereof and independently turnable therearound, the inner ends of said shanks being arranged for co-operation with said carrier whereby rotation of either one of said shanks will move said carrier and withdraw the spindle from its 30 extended position.

7. A lock of the character described including a bolt carrier adapted for lengthwise reciprocation to and from extended position, 35 and a non-rotatable spindle arranged axially perpendicular to said carrier and passing therethrough in slidable but non-rotatable engagement.

8. A lock of the character described including a latch bolt carrier arranged for lengthwise reciprocation to and from extended position, and a non-rotatable spindle arranged axially perpendicular to said carrier and passing therethrough in slidable but non-rotatable engagement, with their longitudinal 45 axes intersecting.

9. In a lock of the character described a latch bolt carrier adapted for reciprocation to and from extended position, a latch bolt 50 adjustably mounted in said carrier, adjustable longitudinally thereof, a protective casting for said carrier and bolt, a rectangular opening through said bolt carrier transversely thereof, a bumper arranged in said carrier for limiting the retractive movement thereof, a spring support carried by said carrier, a coil spring between said spring support and said bolt adapted to maintain the same normally in its extended position; a 55 spindle extending at a right angle to said carrier and passing through the rectangular opening in the bolt carrier slidably but non-rotatably therein, an auxiliary retractor member rotatably mounted upon one end of 60 said spindle, a locking key member slidably 65

mounted in said spindle to slide lengthwise thereof and having a locking plate projecting through the side wall thereof adapted for engagement with one side of said carrier and be held thereby in its locked position, a sleeve 70 surrounding each end of said spindle each terminating at its inner end at the side, of said carrier, abutments on the sides of said carrier, retractors on the inner ends of said sleeves adapted to coact with said carrier 75 abutments to retract said carrier upon the rotation of said sleeves, and a slit in the inner end of one of said sleeves adapted to receive a portion of said locking plate to lock said sleeve against rotation relative to said 80 spindle.

10. A lock of the character described including a latch bolt carrier arranged for lengthwise reciprocation to and from extended position, a non-rotatable spindle arranged axially perpendicular to said carrier and passing therethrough in slidable but non-rotatable engagement and having their longitudinal axes intersecting, means mounted 85 upon each end of said spindle adapted to be rotated independently of each other to reciprocate said latch bolt carrier from extended position, means between said spindle and one of said bolt reciprocating means for locking the same against relative rotation, means 90 for normally yieldably holding said carrier in its extended position, and a latch bolt adjustably mounted in said carrier.

11. A lock of the character described including a latch bolt carrier arranged for lengthwise reciprocation to and from extended position, a latch bolt mounted in said carrier, a non-rotatable spindle arranged axially perpendicular to said carrier and passing centrally therethrough in slidable but non-rotatable engagement therewith, means to yieldably maintain said bolt carrier and bolt 100 in their extended positions, means rotatably mounted on each end of said spindle, rotatable therearound, adapted to reciprocate said bolt carrier, means to lock one of said last means against rotation relative to said spindle, and an auxiliary reciprocating member 105 mounted in one end of said spindle for releasing said last means.

12. A lock of the character described including a latch bolt carrier arranged for lengthwise reciprocation to and from extended position, a non-rotatable spindle arranged axially perpendicular to said carrier and passing therethrough in slidable but non-rotatable engagement with their longitudinal axes intersecting, a latch bolt carried by said carrier, means to yieldably maintain said carrier and bolt in their extended position, means rotatably mounted on said spindle, one on each end thereof adapted when rotated to reciprocate said carrier and bolt, means mounted in said spindle adapted for manual operation to lock one of said rotating 110 115 120 125 130

means to said spindle to prevent rotation of said rotating means, a slit in the end of said last rotating means for coaction with said locking means, and a cross bar carried by
5 said latch bolt carrier adapted to hold said locking means in its operating position when said carrier is in its extended position, and an auxiliary reciprocating member mounted in said last rotating means for reciprocating
10 said latch bolt carrier to release said locking means.

In witness that I claim the foregoing I have hereunto subscribed my name.
